Primary Examiner — Shawn T Gingrich*Assistant Examiner* — Bryan N. Melvin*(74) Attorney, Agent, or Firm* — David Nocilly(57) **CLAIM**

We claim the ornamental design for a multi voltage power panel and power distribution center, as shown and described.

DESCRIPTION

FIG. 1 is a front perspective view of a multi voltage power panel and power distribution center;

FIG. 2 is a front view thereof;

FIG. 3 is a rear view thereof;

FIG. 4 is a left side view thereof;

FIG. 5 is a right side view thereof;

FIG. 6 is a top plan thereof; and,

FIG. 7 is a bottom plan thereof.

The broken lines in the drawings illustrate portions of the multi voltage power panel and power distribution center that form no part of the claimed design.
